REPEATER FOR ROLLING MILLS

Walter U. Boedeker, Chicago, and Walter G. Seid-
litz, Oak Park, Ill., assignors to Western Elec-
tric Company, Incorporated, New York, N. Y., a
corporation of New York

Application May 10, 1932, Serial No. 610,366

11 Claims. (Cl. 80—52)

This invention relates to a repeater for rolling mills, and more particularly to a repeater for intermediate and finishing passes of rod mills.

An object of the present invention is to pro-
vide a simple, inexpensive and efficient repeater
for rolling mills.

One embodiment of the invention contemplates the provision of an arcuate shaped track of chan-
nel cross-section for guiding rods between suc-
cessive reducing passes of rod mills, the track be-
ing formed of a plurality of interchangeable por-
tions removably secured to a one-piece base por-
tion and having tapered overhanging surfaces
for holding the rod in process in the track until
15 its forward end enters the next pass. A delivery spout of U-shaped cross section directs the
rod into the entrance end of the track and is
provided with a pivoted inverted U-shape cover
carrying a pivoted spring pressed retaining finger
20 for holding the rod to a path communicating with
the track until the forward end of the rod enters
the next pass and then allows the rod loop be-
tween the passes to move free of the track and
into a looping pit, as the rod loop increases in
25 length. An exit spout similar to the delivery
spout guides the rod from the exit end of the
track into the entrance guide of the next pass
and has formed on its cover a grease reservoir
30 which slants downwardly toward the entrance
guide of the mill, whereby the grease melted
by the heat from the hot rod being processed
flows into and lubricates the entrance guide of
the mill. A guard positioned at the exit end of
35 the track serves to prevent rods from approach-
ing the next pass unless their forward ends have
properly entered the entrance guide thereof and
also prevents the rods from whipping over the
rolls of the mill after they leave the preceding
40 pass.

Other objects and advantages of the invention
will be apparent from the following description
taken in conjunction with the accompanying
drawings, wherein

Fig. 1 is a top plan view of a rolling mill re-
peater embodying the features of the invention;

Fig. 2 is an end elevational view thereof;

Fig. 3 is a side elevational view, partly in sec-
tion, of one of the delivery spouts, the view being
taken along the line 3—3 of Fig. 1;

Fig. 4 is a side elevational view, partly in sec-
tion, of one of the exit spouts, the view being
taken along the line 4—4 of Fig. 1;

Fig. 5 is a fragmentary side elevational view of
the repeater;

Fig. 6 is a sectional view of one of the delivery

spouts, the view being taken along the line 6—6
of Fig. 3;

Fig. 7 is a sectional view of one of the exit
spouts, the view being taken along the line 7—7
of Fig. 4; and

Figs. 8 and 9 are cross-sectional views of the
tracks taken along lines 8—8 and 9—9, respec-
tively of Fig. 1.

Referring now to the drawings wherein like
reference numerals designate similar parts
throughout the various views, reference numerals
10 and 11 designate successive sets of reducing
rolls having cooperating peripheral grooves form-
ing successive passes of a rolling mill for reduc-
ing rods. The invention lies in a repeater for
receiving rods from the reducing rolls 10 and di-
recting the rods to the reducing rolls 11. In one
embodiment the repeater consists of delivery
spouts indicated generally at 12 and 13, tracks
14 and 15, a guard or safety monument indicated
generally at 16, which extends over the tracks
adjacent the exit ends thereof, and exit spouts
indicated generally at 17 and 18.

The delivery spouts 12 and 13 are identical
in construction and, therefore, a description of
one will apply equally well to them both. In Fig.
3 a side elevational view of the delivery spout
13 is shown having a lower portion 20 U-shaped
in cross-section and having one end secured to a
bracket 21 which is fixedly mounted upon a de-
livery pipe 22, while the other end is removably
secured, by means of an adjustable clamp 23,
to a projection 24 at the entrance ends of the
tracks 14 and 15. The bottom wall of the lower
portions 20 has an opening 25 therein adjacent
the receiving end of the delivery spout for allow-
ing foreign particles, such as scaling from the rod
being processed, to drop therethrough. The de-
livery pipe 22 is fixedly carried by a bracket 27
and extends to a position between the rolls 10 to
receive the rod passing therebetween.

A cover 30 is U-shaped in cross-section and ex-
tends over the lower portion 20 of the delivery
spout 13. The cover 30 is pivotally mounted at one
end at 31 upon the bracket 21 and pivotally car-
ries at its other end a retaining finger 32 pro-
vided with an arcuate-shaped rod engaging end
33 normally urged toward the track 15 by a spring
34. The weight of the cover 30 is sufficient to hold
the rod to a path communicating with the en-
trance end of the track 15 until the forward end
thereof enters the next pass but is not sufficient
to thereafter prevent the rod loop between the
passes from moving free of the track and into
the looping pit (not shown), as the rod loop in- 110

creases in length due to the reduction in the cross-section thereof. To vary the retaining power or the effective weight of the cover 30, a spring 35 is employed, which has one end fixed to a projection 36 of the cover 30, while the other end is fixed to an adjusting screw 37 extending through a threaded aperture of a bracket 36 integral with the lower portion 20.

The tracks 14 and 15 have their lower or base portions 39 formed of a single casting with grooves arcuate shaped in general contour and U-shaped in cross-section. The upper portions of the tracks 14 and 15 are formed of arcuate shaped removable and interchangeable members, some of which, indicated at 40, have overhanging retaining lips 41 to hold the rod, being advanced from one pass to the other, within the desired track until the forward end of the rod passes between the rolls 11. In order that rods, being advanced through either track 14 or 15, may move free of the tracks when the forward ends of the rods have entered between the rolls 11, the upper track members indicated at 42 and 43 adjacent the receiving end of the tracks do not have the overhanging lip portions for retaining rods in the tracks. In the present instance, the next set of upper track members indicated at 44 and 45 have their inner edges from approximately the center thereof to the right ends thereof provided with overhanging tongue portions which gradually merge into flat or tongueless portions adjacent the center thereof. The upper track members 43 and 45, as well as an upper track member 46, project outwardly to form an apron or platform over the track 14 so that a rod may escape from the track 15 without interfering with a rod passing through the track 14.

The guard or safety monument 16 has a horizontally extending portion 47 which extends over the tracks 14 and 15 and provides a guarded passageway 48 for the rods. A head portion 50 is integral with the portion 47 and has upper walls which extend downwardly from the center thereof, as indicated at 51 and 52. The head portion 50 has projecting fingers 53 and 54 which extend over rod receiving recesses 55 and 56, respectively. At each side of the head portion 50 are upwardly projecting retaining arms 57 and 58 having inwardly and downwardly extending surfaces 59 for a purpose hereinafter described.

The exit spouts 17 and 18 are identical in construction and, therefore, a description of one will apply equally well to them both. In Fig. 4, the exit spout 18 is shown in elevation in association with the track 14 and the rolls 11. The exit spout 18 consists of a lower portion 65 which is U-shaped in cross-section and has one end removably secured to a projection 66 of the lower portion 39 of the tracks 14 and 15 by means of a clamp 67, while the other end extends into and is supported by a rod guide 68. The lower wall of the portion 65 has an opening 69 for allowing material scaling from the rod to drop therethrough so that this material will not be forced into and obstruct the free passage of the rod through the guide 68. The rod guide 68 is supported by a suitable holder or bracket 70 and terminates at a position between the rolls 11 to accurately guide a rod between the rolls.

A cover 73 is provided for the lower portion 65 of the exit spout, this cover being H-shaped in cross-section, the horizontal connecting portion 74 of which rests upon the vertical walls of the lower portion 65 to completely surround rods passing through the exit spout. The downward-

ly projecting walls of the cover 73 have tapered forward ends 75 extending beneath tapered surfaces 76 of lugs formed upon the vertical walls of the portion 65. The upwardly extending walls of the cover 18 together with the connecting portion 74, form a grease containing compartment indicated generally at 77 for grease 78 used for a purpose hereinafter described.

During the operation of the repeater, let it be assumed that a rod 26 is fed between the rolls 10 and 11 and directed through the delivery pipe 22 and into the delivery spout 12. The rod in passing through the spout 12 will be directed into the track 14 and held in the track by the retaining finger 32, which rests upon the rod during the advancement thereof. The rod will then pass through the track 14, while being held therein by the overhanging tongue portions 41 of the upper track members 40, through the guarded passageway 48 and enter the exit spout 18. Even though the cover 73 of the exit spout 18 merely rests upon the lower portion 65, its weight is sufficient to hold the rod in the exit spout and direct it through the rod guide 68 and between the rolls 11. It is to be understood that the rod 26 is heated to a desired temperature prior to the rolling operations and heat from the rod while passing through the exit spout 18 will heat the walls thereof and slowly liquefy the grease 78, which will drip into the portion 65 of the exit spout 18 adjacent the rod guide 68, thus lubricating the exit end of the spout 18 and the rod guide 68.

As soon as the forward end of the rod 26 enters the rolls 11, the rod between the sets of rolls 10 and 11, which, up to this time is positioned in the delivery spout 12, the track 14, and the exit spout 18, begins to increase in length. This increase in length of the rod 26 would cause it to buckle in the delivery spout 12, moving the cover 30 upwardly about its pivot 31, moving with it the retaining finger 32 and allowing the rod to move free of the track 14 at the entrance end thereof. As described above, the upper track member 42 and a part of the upper track member 44 do not have the retaining lip portions 41 making it possible for the rod to move free of the track at this position, and as soon as the rod starts to move free of the track, the tapered retaining tongue of the upper track member 44 will make it possible for the rod to move free of the remaining portion of the track. The loop of the rod between the rolls 10 and 11 will then extend down the looping pit (not shown).

One of the functions of the safety monument 16 is to prevent the tail end of the rod from whipping over the rolls 11 after it has passed from between the rolls 10. Another function of the safety monument 16 is to provide auxiliary guides for rods which fail to enter the rolls 11 after passing between the rolls 10. If a rod should fail to enter the rolls 11, the rod is given a zig-zagging movement down the looping pit by the operator until the tail end thereof passes from between the rolls 10, after which the operator grasps this end of the rod with a suitable tool, directs it through either of the exit spouts 17 and 18 as, for example, the exit spout 18, until the end of the rod is gripped by the rolls 11 and advanced therebetween. In feeding the end of the rod through the exit spout 18 and between the rolls 11, the portion of the rod positioned over the safety monument is positioned upon the surface 52 of the head 50 or the tapered surface 59 of the arm 58 where the rod will be directed downwardly and beneath the projection 54 and into 150

- the retaining recess 56. During the movement of the rod while in this position, the safety monument not only prevents the rod from whipping over the rolls 11 but also tends to straighten the 5 rod before it passes through the exit spout 18 and between the rolls. It is to be understood that the exit spout 17 may be used for the same purpose, in which case the rod will be placed either upon the tapered surface 51 of the head portion 10 50, or the tapered surface 59 of the arm 57, where it will be directed downwardly beneath the projection 53 and into the recess 55.
- During the movement of the rod through the delivery spout 12, the track 14, and the exit spout 15 18, another rod may be advanced through the delivery spout 13, the track 15 and the exit spout 17. It is not probable that these rods will be started in their travel through the repeater simultaneously, but it is probable that one rod will be 20 fed between rolls 10, before the preceding rod has passed completely from between the rolls 10. When this occurs, the apron formed by the projections of the upper track members 43, 45 and 46 of track 15, and which extends over the track 25 14, permits the rod to move free of the track 15 without interfering with the rod in the track 14. Furthermore, the safety monument 16 provides a safety means for both tracks and provides means whereby successive rods may be directed through 30 the exit spouts 17 and 18 by the operator, these rods being straightened while passing through the recesses 55 and 56. The cause of a rod failing to enter between the rolls 11 may be from an enlarged forward end which may result from a 35 knot in the rod.
- This repeater may be employed for various passes of the rolling mill and for processing rods composed of various materials. When the repeater is used for some passes, the weight of the 40 cover 30 of each of the delivery spouts 12 and 13 is sufficient to hold the rods therein until the forward ends have entered the next pass, but when using the repeater for later or finishing passes, it is necessary to vary the downward force of 45 the covers 30 which is brought about by varying the tension of the springs 35 through the adjustment of the screws 37.
- An important feature of this repeater is the formation of the lower portions of the tracks with 50 one piece of material, such as the casting, and the forming of the upper portions of the tracks by a plurality of arcuate shaped elements equal in length and arranged to be interchangeably secured to the lower portion so that these portions, 55 when they become worn, may be removed, and other like portions substituted therefor; and so that the upper portions may be interchanged depending upon the characteristics of the rods being advanced through the tracks. As shown in Fig. 60 1, the retaining lips 41 start at approximately the centers of the upper track members 44 and 45 and continue to the exit ends of the tracks 14 and 15. This arrangement is desired for a certain type of rod, such as one form of copper, but a different 65 arrangement may be desired for a rod formed of other material. Furthermore, the shape of the retaining lip 41 may be varied, depending upon the cross-sectional contour of the rod.
- While the invention has been described with 70 reference to a specific embodiment thereof, it is obvious that various modifications may be made therein without departing from the spirit and scope of the present invention.
- What is claimed is:
- 75 1. In a repeater for rolling mills, a substantially U-shaped track, and delivery spout for delivering the forward end of a rod from one set of reducing rolls of a rolling mill to said track, said delivery spout comprising a stationary portion, and a movable portion cooperating with said stationary portion for directing a rod into said track and movable by the rod when caused to buckle by the forward end entering another set of reducing rolls, whereby the rod may readily escape from said track. 80
2. In a repeater for rolling mills, a substantially U-shaped track for receiving a rod from one pass of a rolling mill and directing the rod to a subsequent pass thereof, a delivery spout for delivering the rod from a preceding pass to said track, said spout including a yieldably mounted cover, and means yieldably carried by said delivery spout cover for holding the rod in the track. 85
3. In a repeater for rolling mills, a substantially U-shaped track for receiving a rod from one pass of a rolling mill and directing the rod to a subsequent pass thereof, and a delivery spout for receiving the rod from the first of the two passes and directing the rod into said track, said delivery spout comprising a stationary member, a movable member arranged to hold the rod in said stationary member until the forward end of the rod enters the subsequent pass and movable by the rod due to buckling caused by an increase in length of the portion of the rod between the 100 passes, whereby the rod may escape from said track. 105
4. In a repeater for rolling mills, a track for receiving a rod from one pass of a rolling mill and directing the rod to a subsequent pass thereof, and a delivery spout for receiving the rod from the first of the two passes and directing the rod into said track, said delivery spout comprising a stationary member, a movable member for retaining the rod in said stationary member until 110 the forward end of the rod enters the subsequent pass and movable by the rod due to buckling caused by an increase in length of the portion of the rod between passes, whereby the rod may escape from said track, and means for varying 115 the retaining force of said movable member.
5. In a repeater for rolling mills, a track for receiving a rod from one pass of a rolling mill and directing the rod to a subsequent pass thereof, a delivery spout for delivering the rod from 120 the first of the two passes to said track, said delivery spout comprising a stationary member secured to said track, a movable member normally held by gravity in engagement with said stationary member and cooperating with said stationary member for directing the rod into said track, and means for varying the force of the movable member toward said stationary member. 125
6. In a repeater for rolling mills, a guide track 130 for receiving a rod from one pass of a rolling mill and directing the rod to a subsequent pass thereof, and a safety guard extending over said track for holding the rod within a predetermined path during the advancement thereof, said guard having a recess for receiving a rod not delivered by said track but directed to said subsequent pass for holding said rod in a predetermined path, a downwardly inclined upper surface on said guard, and an arm carried by said guard having a free 140 end thereof spaced from said inclined surface intermediate its length, said surface and arm cooperating to guide the rod into the recess. 145
7. In a repeater for rolling mills, a substantially U-shaped track for receiving a rod from 150

one pass of the rolling mill and directing the rod to a subsequent pass thereof, and a safety guard extending over said track adjacent the exit end thereof for holding the rod within a predetermined path during the advancement thereof, said guard having means for removing kinks from a rod directed to said subsequent pass.

8. In a repeater for rolling mills, a track for receiving a hot rod from one pass of a rolling mill and directing the hot rod to a subsequent pass thereof, an exit spout positioned between said track and the subsequent pass for receiving the hot rod from said track and directing it to said subsequent pass, and means for containing a lubricant so designed and positioned relative to said exit spout that the lubricant may be liquefied by the heat of the rod and drip onto said exit spout for lubricating the same.

9. In a repeater for rolling mills, a track for receiving a rod from one pass of a rolling mill and directing the rod toward a subsequent pass thereof, an exit spout for receiving the rod from said track, a guide for receiving the rod from said exit spout and directing the rod to said subsequent pass, and means carried by said exit spout for containing a lubricating material for lubricating the exit end of said exit spout and said guide.

10. In a repeater for rolling mills, a track for receiving a hot rod from one pass of a rolling mill and directing the hot rod toward a subsequent pass thereof, an exit spout for receiving the hot rod from said track, a guide for receiving the hot rod from said exit spout and directing it to said subsequent pass, and means carried by said exit spout for containing a lubricant to be liquefied by the heat from the hot rod passing through said exit spout for lubricating a portion of said exit spout and said guide.

11. In a repeater for rolling mills, a track for receiving the rod from one pass of a rolling mill and directing the rod to a subsequent pass thereof, a delivery spout for delivering the rod from a preceding pass to said track, said spout including a yieldably mounted cover, means yieldably carried by said delivery spout cover positioned to engage the rod while entering said track for holding the rod in said track until the forward end thereof enters the subsequent pass and thereafter movable to allow the rod to escape from said track, and means for varying the force of said holding means in engagement with the rod.
